DESIGN FOR A FISHING REEL

Henry I. Mandolf, San Diego, Calif.

Application November 26, 1945, Serial No. 124,091

Term of patent 14 years

(CL. D31—4)

To all whom it may concern:

Be it known that Henry I. Mandolf, a citizen of the United States of America, residing at San Diego, in the county of San Diego and State of California, has invented a new, original, and ornamental Design for a Fishing Reel, of which the following is a specification, reference being had to the accompanying drawing forming a part thereof.

Figure 1 is a side elevational view of a fishing reel, showing my new design; Fig. 2 is an end view of the fishing reel; and Fig. 3 is a side view opposite that shown in Fig. 1 on a slightly reduced scale.

I claim:

The ornamental design for a fishing reel, substantially as shown.

HENRY I. MANDOLF.
